UNITED STATES PATENT OFFICE.

CHARLES G. BUDER, OF ST. LOUIS, MISSOURI, ASSIGNOR TO HAYNES-LANGENBERG MFG. CO., OF ST. LOUIS, MISSOURI, A CORPORATION OF MISSOURI.

HOT-AIR FURNACE.

Application filed April 11, 1924. Serial No. 705,791.

To all whom it may concern:

Be it known that I, CHARLES G. BUDER, a citizen of the United States, residing at St. Louis, Missouri, have invented a new and useful Hot-Air Furnace, of which the following is a specification.

This invention relates to improvements in hot air furnaces, and consists in the novel construction hereinafter disclosed.

- 10 An object of the invention is to provide a forced draft circulatory system for a hot air furnace in which the blower device generates and introduces into the furnace casing a volume of air, said casing being interiorly provided with baffles adapted to direct the currents of air about the heating element of the furnace in such manner as to obtain the maximum heating efficiency from the apparatus.
- 15 Another object of the invention is to provide in connection with a furnace a blower apparatus having spaced fan elements arranged to generate converging currents of air for introduction into the furnace, which blower apparatus is so arranged that when the same is not in operation there will be a normal supply of air through the apparatus for introduction into the furnace.

20 Additional advantages of the construction will be apparent from the detailed description taken in connection with the accompanying drawing, in which—

Fig. 1 is a plan view with the casing of the furnace partially in section.

25 Fig. 2 is a vertical section through the furnace.

Fig. 3 is a vertical section through the furnace taken at right angles to Fig. 2.

30 Fig. 4 is a vertical section through the blower device.

Fig. 5 is a detailed view of the blower fan construction.

The furnace proper includes a casing 1 in which is mounted a fire drum 2 with radiators 3 arranged in communication therewith and offset rearwardly from the drum. At the bottom of the radiators and connecting the same is a dust box 4 upwardly from which extends the smoke pipe 5. It will be noted that the radiators are spaced rearwardly from the drum and are connected therewith by communicating passages 6 and that the dust box extends around the rear segment of the drum from which it is spaced,

thereby forming a passage way between the 55 dust box and the side wall of the drum.

At the rear of the casing 1 there is an opening into which is connected the blower device housing 7. The blower device housing comprises a substantially cylindrical 60 shell the forward part of which matches the edges of the opening in the back of the furnace casing, it being observed that there is an inlet opening from the blower housing into the furnace. The blower housing is provided with end members 8 having central openings and into which are fitted annular flanges 9, thereby forming at each end of the blower casing air inlet openings for the introduction of air into the blower device. 65 Extending upwardly from the lower part of the annular flanges 9 are brackets 10 that support bearing members 11 for the fan shaft. The shaft 12 extends transversely of the blower device and is journaled at each 70 end in the bearings 11 respectively, one end of the shaft extending beyond one end of the blower housing, said extending end carrying a pulley 13 constituting a drive pulley for the shaft 12. The pulley 13 is driven by 75 a belt 14 that operates over a pulley 15 on a motor shaft 16, the motor M preferably being mounted on the upper wall of the blower housing 7.

The fan devices of the blower are duplicate in construction, the inner ends thereof being spaced apart. The fans proper include discs 17 mounted fast on the shaft 12. Extending outwardly from the discs 17 are a plurality of curved blades 18, the outer ends 80 of the curved blades being connected together by rings 19.

It will thus be observed that there is free passage into each of the fan devices through the opening formed by the flanges 9 and 85 outwardly between the blades 18 of the fans. When the blower device is operated converging currents of air are generated and are expelled outwardly from the bottom of the opening between the blower housing and the 90 furnace casing into the furnace casing, it being understood that the direction of rotation of the fans is that indicated by the arrow in Fig. 2.

The peculiar construction of the spaced 105 fan devices builds up converging currents of air that meet at the opening into the furnace casing and thereby prevents any suc-

tion in the blower device, causing the currents of air generated by the blower device to be expelled forwardly into the casing of the furnace. Additionally it will be observed that the combined area of the openings within the flanges 9 is relatively large, providing for a normal inlet of air through the fan elements of the blower and into the casing of the furnace when the blower device is not under power.

Within the furnace casing and so arranged as to cause a complete diffusion of the air currents about the surface of the heated elements of the furnace are a series of baffle plates. There are spaced on either side of the normal line formed by the outer edges of the converging currents a pair of inclined baffle plates 20. The baffle plates 20 diverge inwardly and are inclined upwardly from the opening into the furnace casing, the outer ends thereof being spaced above the bottom of the opening from the blower housing to the casing, so that a portion of the inflowing current of air will be deflected forwardly into the furnace casing so as to contact with the fire drum of the furnace, thereby heating the currents of air thus deflected as they rise in the casing of the furnace.

Within the space between the inner edges of the baffle plates 20 and arranged vertically are a pair of baffle plates 21 that converge inwardly toward the fire drum of the furnace, said baffle plates deflecting the converging currents of air from the blower in such a way as to cause a portion of the volume of air thus introduced to rise in the space between the drum and the radiators of the furnace.

It will thus be seen that the invention provides for the introduction of converging currents of air into the furnace casing and of so controlling the currents thus introduced into the furnace casing as to cause a complete circulation of the air currents about the heat surfaces of the furnace. Additionally, it will be observed that it is a considerable advantage to have the blower construction designed so that when it is not under power there remains a direct passage way through the blower for a volume of air for normal feed into the furnace casing.

This construction results in a very high degree of efficiency, very materially increasing the heat generated by the furnace over that generated by a single fan blower device, and over an unbaffled interior construction of furnace casing.

I am aware that the invention may be modified in certain particulars without departure from the spirit and scope thereof.

What I claim and desire to secure by Letters Patent is:—

1. In a furnace comprising a fire drum and a casing enclosing and spaced from the

fire drum and having an air inlet opening through one side and near the lower end thereof, a pair of baffle plates extending inwardly and upwardly from said opening and having their inner edges spaced from the fire drum and their outer edges contacting with said casing, and a pair of approximately vertical baffle plates having their inner edges adjacent to the fire drum above the planes of said first baffle plates, 75 said second pair of baffle plates diverging outwardly in planes intersecting said casing laterally from said opening.

2. In a furnace comprising a fire drum and a casing enclosing and spaced from the fire drum and having an air inlet opening through one side and near the lower end thereof, a pair of baffle plates extending inwardly and upwardly from said opening and having their inner edges spaced from the fire drum and their outer edges contacting with said casing, and a pair of approximately vertical baffle plates having their inner edges adjacent to the fire drum above the planes of said first baffle plates, 80 said second pair of baffle plates diverging outwardly in planes intersecting said casing laterally from said opening, the outer edges of said second baffle plates terminating in 85 a plane inwardly from the plane of the inner edges of said first baffle plates.

3. In a furnace comprising a fire drum and a casing enclosing and spaced from the fire drum and having an air inlet opening through one side and near the lower end thereof, a pair of baffle plates extending inwardly and upwardly from said opening and having their inner edges spaced from the fire drum and their outer edges contacting with said casing, a pair of approximately vertical baffle plates having their inner edges adjacent to the fire drum above the planes of said first baffle plates, 90 said second pair of baffle plates diverging outwardly in planes intersecting said casing laterally from said opening, and means for forcing air through said opening below and above said first baffle plates and into contact with said second baffle plates.

4. In a furnace comprising a fire drum and a casing enclosing and spaced from the fire drum and having an air inlet opening through one side and near the lower end thereof, a pair of baffle plates extending inwardly and upwardly from said opening and having their inner edges spaced from the fire drum and their outer edges contacting with said casing, a pair of approximately vertical baffle plates having their inner edges adjacent to the fire drum above the planes of said first baffle plates, 105 said second pair of baffle plates diverging outwardly in planes intersecting said casing laterally from said opening, and means for forcing air through said opening below and above said first baffle plates and into contact with said second baffle plates.

- a plane inwardly from the plane of the inner edges of said first baffle plates, and means for forcing air through said opening below and above said first baffle plates and 5 into contact with said second baffle plates.
5. In a furnace comprising a fire drum and a casing enclosing and spaced from the fire drum and having an air inlet opening through one side and near the lower end 10 thereof, a pair of baffle plates inclining inwardly and upwardly from said opening and having their inner edges diverging and out of contact with said fire drum, a second pair of baffle plates having their inner edges 15 adjacent to said fire drum and having their inner ends below the planes of said first baffle plates and their lower edges inclining outwardly and upwardly to an intersection with their outer edges above the planes of 20 said first baffle plates, said second baffle plates diverging outwardly in planes intersecting said casing laterally from the side edges of said opening.
6. In a furnace comprising a fire drum 25 and a casing enclosing and spaced from the fire drum and having an air inlet opening through one side and near the lower end thereof, a pair of baffle plates inclining inwardly and upwardly from said opening and having their inner edges diverging and out of contact with said fire drum, a second pair of baffle plates having their inner edges 30 adjacent to said fire drum and having their inner ends below the planes of said first baffle plates and having their lower edges inclining outwardly and upwardly to an intersection with their outer edges above the planes of 35 said first baffle plates and having their lower edges inclining outwardly and upwardly to an intersection with their outer edges above the planes of said first baffle plates, said second baffle plates diverging outwardly in planes intersecting said casing laterally from the side edges of said opening, and means for forcing air through said opening below all of said baffle plates.
7. In a furnace comprising a fire drum and a casing enclosing and spaced from the fire drum and having an air inlet opening through one side and near the lower end 40 thereof, a pair of baffle plates inclining inwardly and upwardly from said opening and having their inner edges diverging and out of contact with said fire drum, a second pair of baffle plates having their inner edges 45 adjacent to said fire drum and having their inner ends below the planes of said first baffle plates and having their lower edges inclining outwardly and upwardly to an intersection with their outer edges above the planes of said first baffle plates, said second baffle plates diverging outwardly in planes intersecting said casing laterally from the side edges of said opening, and means for forcing air through said opening below all of said baffle plates, and above 50 said first baffle plates and against said second baffle plates.

CHARLES G. BUDER.
